WINDOW LOCK CONSTRUCTION

James L. Davidson, Los Angeles, Calif.

Application August 13, 1937, Serial No. 158,949

2 Claims. (Cl. 292—57)

This invention relates to improvements in window construction, and particularly to that type commonly known as a double-hung sash or English sash.

The invention has for an object the provision of a double-hung type window and its sash which allows ready cleaning of the window sash through the mere expediency of a certain construction which converts said window into the casement sash or French sash type.

At the present time in office buildings, the double-hung sash or English sash window is generally utilized, particularly where the sash is formed of wood. When it becomes necessary to clean a glass window mounted in a sash of this character, the window washer, as a rule, cleans the outside of the glass window while utilizing a safety belt. Statistics show that safety belts are not always reliable and numerous deaths result through carelessness of the window washer either not fastening the belt correctly, by slipping, or other causes. Furthermore, it is practically impossible for a window washer to obtain any insurance, and if insurance is obtained, the premium is generally very high.

An object of the present invention is to provide a double-hung type window having its parts so constituted and arranged that the weight members generally used for counter-balancing the window sash may be locked in a given position and the individual window sashes moved inwardly or outwardly, as the case may be, whereby either or both sides of the glazed window sashes may be contacted.

The inventor is aware that various means have been utilized to provide either a casement window sash or a double-hung window sash, but so far as the inventor is aware, no simple means, inexpensive in cost of manufacture, is now on the market capable of quickly and reliably releasing the double-hung window sash so that it may be used as a casement type window sash. The invention is, of course, of great utility for the housewife, in that it becomes a simple matter to wash the glass window, and is particularly useful during any type of weather when a casement type window would be more desired than a double-hung type window. For instance, in hot weather or cold weather, a casement window sash permits an opening adapted to allow air to enter a room and at the same time deflect the air current to prevent drafts upon a person. The double-hung window sash is not so readily utilized for this purpose, and furthermore, the double-hung type window will only allow one

window sash opening and not a full length opening.

An object of the invention is to provide certain hardware which may be utilized with a double-hung window sash of the standard type, and which hardware is so constructed as to be very cheap in cost of manufacture, as well as the retail price of furnishing the same. When cheapness is considered, together with the advantages of a window sash construction of the type to be hereinafter described, together with the safety factors involved, the inventor feels that a distinct step has been made in this particular art over devices which are more cumbersome and quite expensive, both to make and to install. With the present invention, an ordinary carpenter can install the particular mechanism adapted to perform the function of the invention, to wit: to provide a duofold window sash which may be either of casement or double-hung type at the will of the individual user.

By way of description, it may be stated that the ordinary type of window sash may be utilized, such sash comprising spaced-apart parallel stiles interconnecting with top and bottom rails. Both of the stiles are in two parts, the two parts of one being hinged together, and the two parts of its parallel stile not hinged. I provide, in addition, the usual sash weights, and a means constituting a portion of the present invention, whereby the outermost portion of the hinged and not hinged two-part stiles both may be locked to the window frame and particularly to the pulley stiles, and at the same time release the other portion of the sash stiles to permit the window sash to swing in one direction through the medium of the hinges, the pulley weights being held against movement when the sash is swung. In a second operation, the means previously mentioned interlocks the two portions of the stiles and in so doing, releases the sash weights so that the window sash as an entirety, may constitute what is called the usual double-hung sash to permit it being raised or lowered relative to the window frame. This contemplates the invention in its simplest embodiment.

Other objects of the invention will be apparent to those who have need for a window sash of the type mentioned, and it may be pointed out that the present type of construction permits a screen to be permanently attached to the outside architrave, which is a safety factor in that when the screens are of sufficient weight, access through the window is prevented, thus eliminat-

ing petty thievery and still the window sash may be raised and lowered, or used as casements, and both sides of the glazed sash may be readily cleaned.

The device, while particularly adapted for window construction, is also readily adaptable for door construction where, under certain circumstances, it is desired to lift or elevate the door straight upwardly or to permit the door to be lowered and act as a swing door.

In addition to inexpensiveness in cost of manufacture, ready adaptability to various uses, whether for window, door, or the like, the invention consists in the novel and useful provision, construction, association, and relative arrangement of parts, members and features, all as shown in certain embodiments in the accompanying drawings, described generally, and more particularly pointed out in the claims.

In the drawings:

Figure 1 is a fragmentary elevation, partly in section, of a double-hung sash incorporating casement features.

Figure 2 is a sectional view on the line 2—2 of Figure 1.

Figure 3 is a perspective view of means adapted to cooperate with the window sash and frame whereby when said means is operated, the window sash may operate as a double-hung or English type or as a casement or French type.

Figure 4 shows a portion of the means of Figure 3 in a changed position, and,

Figure 5 is a sectional view on the line 5—5 of Figure 3.

Referring now to the drawings, I have shown in Figures 1 and 2 a window frame 1 of conventional appearance and of the type which may be utilized for the ordinary double-hung sash. Referring to Figure 1, 1 designates generally the inside window frame and 2 the outside window frame. The vertical outside casing members 3 and 4 of the outside window frame 2, together with the inside casing members 5 and 6 of the inside window frame 1, and the interconnecting pulley stiles 7 and 8 between the casing members 3 and 5, and 4 and 6, respectively, form what are known as weight boxes or pockets. So far, the construction is usual, and the pulley stiles 7 and 8 are both provided with parting strips 9 and 10, and stop beads 11 and 12. It is customary to permit the outside architrave to project slightly beyond the outer face of the pulley stiles, as shown at 13 and 14. In ordinary practice then, and assuming that pulleys are used and secured by suitable brackets adjacent the top of the weight boxes, as indicated by dotted lines at 15 and 16, and that weights 17 and 18 are in one weight box and weights 19 and 20 in the other weight box, these weights when connected by suitable cords passed over the pulleys, of which 15 and 16 are representative, counter-balance in the usual manner the sashes, here designated as entireties by 21 and 22. These sashes are guided within suitable sash-receiving grooves, the grooves being formed by the provision of the stop beads and parting strips in one instance, and the parting strips and the architrave, together with the outer face of the pulley stile in the second instance. It is evident that the present sashes would operate in accordance with any double-hung sash, and it is now proposed to so construct the window sash that the same may operate as a casement sash. To accomplish this, I provide certain novel constructional features and means. One sash will be considered, as the

other sash is identically arranged, and the hardware the same.

Taking the sash 21 by way of example, the sash frame constitutes, as is usual, stile members 23 and 24, which usually constitute the vertical portions of the frame, and top and bottom rails interconnecting the stiles indicated at 25 and 26. The glass pane is held between the stiles and rails in the customary manner. The stiles, in 5 each instance, are formed in two cooperating parts and, for convenience, the parts will be designated as 23a and 23b in one instance, and 24a and 24b in the second instance. The stile 23a is movable within the sash receiving groove 10 of the pulley stile, to wit, that portion included between the stop bead 11, the outer face of the pulley stile and the parting strip 9. Connecting the two parts of the stile 23 together, to wit, the parts 23a and 23b, are hinges 27 and 28. For 10 purposes of illustration, these hinges are shown as exposed, and it is evident that any type of hinge may be used in practicing the invention, although in actual practice, the invisible type is preferred, so that the hinge is hidden from view. 15 The stile 24 has the two parts 24a and 24b, and the part 24a is received within the sash receiving groove of the window frame, and particularly the groove included between the parting strip 10, the outer surface of the pulley stile, 20 and the window stop 12, as see Figure 2. The weight cords are, in each instance, secured to the outermost half, to wit, the part 23a and 24a of the sash stiles; in other words, if certain mechanism, to be hereinafter described, was not 25 included, the stile part 24a would move under influence of a counter-balance weight independent of the main window stile 24b. The same would be true for the opposite window stile were it not for the presence of the hinges 27 and 28. 30 In order to operate the device successfully so that the sash may be readily moved as a vertically hung type or as a casement type, I have provided means which may assume the character depicted in Figures 3 to 5, inclusive. This means, 35 characterized generally by the numeral 29, includes a bolt 30 having an elongated shank, and ends 31 and 32 at substantially right angles to the longitudinal axis of the shank. This bolt is of such a shape and length as to bind together 40 two of members 33 and 34, or 34 and 35. These members are in reality a casing or bolt supporting element and two bolt keepers, and taking the first keeper 33, the same includes a flat plate 33a with two half-round portions 33b and 33c 45 forming therebetween a slot 37. The casing 34 includes a plate 38 and a half-round member 39, the edge of which half-round member is spaced from the plate 38 to provide a way or slot 40 to permit assembly of bolt 30 (see Figure 5). The keeper 35 includes a plate 41 formed with a key-way slot 42, and extended outwardly from a surface thereof is a split tube 43. 50 Assuming a position of assemblage for the various members, as illustrated in Figure 3, it will be observed that the shank of the bolt 30 is substantially cylindrical in cross section, as illustrated in Figure 5, and that the way, slot or groove in the casing and each respective keeper is, in each instance, less in cross dimension than the diameter of the bolt. The angled extremity 31 of the bolt, which may be termed the bolt head, is reduced in diameter by diametrically slotting or shouldering the same, as shown at 55 44 so as to readily pass through slot 40 in assembly and slot 37 in operation. The opposite

end of the bolt, to wit, the angular extremity 32, is shaped as a key so as to readily pass through slot 40 in assembling and the keyway slot 42 and the split or way in the member 43 in operation. Thus, in the position shown for the bolt in Figure 3, the key end of the bolt is forward of the plate 41 and the bolt holds together the keeper 33 and casing 34 by the head engaging an end of the member 33c. In Figure 4, the bolt shown in dotted lines has been revolved 90° from the showing of Figure 3, so that the shoulder portion of the head may be received within the slot or way 31, and the key 32 passed through the keyway 42 and the way in the member 43, whereupon the bolt may be revolved 90° to the left, viewing Figure 4, full lines, the key engaging an end of the tube 43, so as to prevent movement of the bolt. In the position shown in Figure 4, the casing 34 and keeper 35 are held together and the keeper 33 is freed from the keeper casing 34.

The members 29, considered as entirities, are placed at four points or zones of the window sash, to wit: the zones indicated by dotted lines at 45, 46, 47, and full lines at 48. Referring to Figure 1, and to that portion indicated at 48, it will be seen that the sash keeper 33 is countersunk inwardly from the upper edge of the top rail. This keeper, as are the casing and remaining keeper, conveniently held in position by means of wood screws or other means passed through openings for this purpose in the respective casing and keepers. The casing 34, to wit, the pulley sash casing, is secured to the member 24a of the window sash, and the pulley stile keeper 35 is secured to the pulley stile, a transverse opening in the stile being provided for this purpose, and the face plate 41 countersunk within the outer face of said stile and held to said stile by wood screws, or the like. Without repetition, it may be said that the arrangement of the means 29 would be the same for the zone marked 47; and for the zones marked 46 and 45, the said means would be just the reverse of the mounting for the zones 47 and 48. In this regard, it may be stated that the means 29, as shown in Figures 3 and 4, are in the positions that they would assume at the zones 45 and 46.

The operation, uses and advantages of the invention are as follows:

When the bolts 30 lie between the keeper 33 and casing 34, the two-part stiles are locked together and either sash may be raised or lowered as desired. When it is desired to operate one of the sashes as a casement, say the sash 21, the sash is raised to a selected position above the stool 49 or to such position that the finger may grasp the head 31 to revolve the bolt, whereby the bolt may be moved longitudinally of the keeper and casing to place the bolt in the position shown in Figure 4. It makes little difference which bolts are first moved, whether it be the bolts at 47 and 48, or the bolts at 45 and 46, but in any event, the stiles 23a and 24a must be locked to the pulley stiles so that the pulley weights are prevented from moving downwardly within the weight boxes or pockets. After the bolts have released the stiles 23b and 24b, the sash may be moved to say, the dotted line presented in Figure 2 at 50. Thus, we have a true casement type window sash.

The operation of the sash 22 is, of course, the same as for the one just described, and while the sashes may be in exact parallelism when this operation occurs, still, in Figure 1, I have for

the purpose of clarity shown the sash 22 as slightly raised above the sash 21. After the sash 21 has had the sash keepers released, it is an easy matter to engage the heads of the means 29 for the sash 22 so that this sash may be swung to the dotted line position shown at 51 in Figure 2. The sash 22 may not assume as great an opening angle as the sash 21. Obviously, the sash 22 will assume a greater opening angle in proportion to the increased width of the keeper member 33a and attached two-part stile member, together with increased length of the bolt 30 of the means 29 for the sash 22 over the width of a like keeper attached to the two-part stile member and bolt of means 29 for the sash 21.

In order that inclement weather may be taken care of, to the end that water shall not pass through the window sash, particularly the portions where the two-part stile portions interconnect, I prefer to rabbet and bevel each stile 24a and 24b as indicated by the lines 52 and 53.

When the windows have been swung, either separately or jointly, as in the case of a casement window, it is a simple matter to clean either side of the pane, as is self-evident. In office buildings, the danger incident to window washers working on the exterior of the buildings is eliminated by a sash of this type, and furthermore, by swinging inwardly, dangers incident to sashes that normally swing outwardly, as they do in certain installations, is a further assurance against accident or falls through a window opening.

Obviously, to return the sash or sashes to the normal double-hung type, the sequence of operations for the members 29 is reversed, to wit, the keeper bolts, say the keeper bolts for the zones 45 and 46, are moved from the position of Figure 4 to that of Figure 3, and the same for the uppermost portions 47 and 48, whereupon the sash weights are again brought into play so that this sash may be moved upwardly or downwardly.

I claim:

1. In a lock of the character disclosed, a casing, two keepers and a lock bolt slidably mounted in said casing so that said bolt may be moved into one locking position extending through said casing and one of said keepers, or into another locking position extending through said casing and said other keeper, angular end portions on the ends respectively of said bolt, so arranged that one of said end portions may engage said casing while the other end portion engages either of said keepers, for locking said bolt against sliding movement while in either of its said locking positions.

2. In a lock of the character disclosed, a casing, two keepers and a lock bolt slidably mounted in said casing so that said bolt may be moved into one locking position extending through said casing and one of said keepers, or into another locking position extending through said casing and said other keeper, angular end portions on the ends respectively of said bolt, and said keepers having ways through which said angular end portions of the bolt may slide respectively, so that when said bolt is in either of its said locking positions it may be turned to cause one of said angular end portions to engage said casing and said other angular end portion to engage one of said keepers to lock said bolt against sliding movement while in either of its locking positions.
